UNITED STATES PATENT OFFICE.

ISAAC W. BIRDSEY, OF BRIDGEPORT, CONNECTICUT, ASSIGNOR TO BIRDSEY,
SOMERS & CO., OF NEW YORK, N. Y.

DESIGN FOR A CORSET.

SPECIFICATION forming part of Design No. 32,418, dated March 27, 1900.

Application filed July 31, 1899. Serial No. 725,696. Term of patent 14 years.

To all whom it may concern:

Be it known that I, ISAAC W. BIRDSEY, a citizen of the United States, residing at Bridgeport, Fairfield county, Connecticut, have invented and produced a new and original Design for Corsets, of which the following is a specification, reference being had to the accompanying drawing, forming a part thereof.

The accompanying drawing shows a side or portion of a corset embodying my new design.

The leading feature of my new design consists of a corset comprising several zones of different ornamental material running transversely around the corset and having separate vertical strips. Thus in the drawing there are three transverse zones *a b c*. The upper zone *a* and the lower zone *c* are shown as having the same ornamental appearance of a somewhat closely-woven network, while the central zone *b* has an ornamental appearance of a some-

what-open-work lace, forming a pleasing contrast with the upper and lower zones. Above and below the central lacework zone are strips *d*. Extending vertically over all the zones are the strips *e*. The whole forms a corset having an ornamental appearance agreeable to the eye.

Having thus described my invention, what I claim as new, and desire to secure by Letters Patent, is—

The design for a corset, as herein shown and described.

In testimony whereof I have signed my name to this specification in the presence of two subscribing witnesses.

ISAAC W. BIRDSEY.
